EDIBLE CONTAINER FOR ICE CREAM AND THE LIKE

Dean A. Smith, Winston-Salem, N.C., assignor to Keebler
Company, a corporation of Delaware

Filed June 23, 1969, Ser. No. 17,805

Term of patent 14 years

Int. Cl. D1—02

U.S. Cl. D1—5

FIG. 1.

FIG. 2.

FIG. 3.

FIG. 1 is a side view of the edible container for ice cream and the like, showing my new design, the other three sides all being the same.

FIGS. 2 and 3 are top and bottom views respectively of the edible container for ice cream and the like.

I claim:

The ornamental design for an edible container for ice cream and the like, as shown and described.
